(57) **CLAIM**

The ornamental design for a putter head, as shown and described.

DESCRIPTION

FIG. 1 is a top front side perspective view of a putter head showing my new design;

FIG. 2 is a front view of the putter head;

FIG. 3 is a top rear side perspective view of the putter head;

FIG. 4 is a top rear side perspective view of the claimed design shown on a second broken line environment;

FIG. 5 is a top front side perspective view of FIG. 4;

FIG. 6 is a top rear perspective view of the claimed design shown on a third broken line environment;

FIG. 7 is a top front perspective view of FIG. 6;

FIG. 8 is a top rear side perspective view of the claimed design shown on a fourth broken line environment; and,

FIG. 9 is a top front side perspective view of FIG. 8.

The undisclosed sides of the putter head form no part of the claimed design. The broken lines shown on the drawings form no part of the claimed design.
